97,416

DESIGN FOR A TEXTILE FABRIC

Samuel Sheindelman, Lawrence, N. Y.

Application July 29, 1935, Serial No. 57,859

Term of patent 3½ years

To all whom it may concern:

Be it known, that, I, Samuel Sheindelman, a citizen of the United States, residing in Lawrence, Nassau County, New York, have invented a new, original, and ornamental Design for Textile Fabrics, of which the following is a specification, reference being had to the accompanying drawing, forming part hereof.

The figure in the drawing is a plan view of a piece of the textile fabric constituting the design.

The design includes a plurality of substantially rectangular areas formed by crossing ribs. The

weave in the ribbed areas is in the nature of a water wave and extends vertically in both the vertical and horizontal ribs. The weave in the intermediate areas is somewhat looser and is in the nature of a waffle stitch. This weave is somewhat irregular, but extends generally in a vertical direction.

I claim:

The ornamental design for a textile fabric as shown and described.

SAMUEL SHEINDELMAN.
